UNITED STATES PATENT OFFICE.

GEORGE H. CAMPBELL, OF CHICAGO, ILLINOIS, ASSIGNOR OF ONE-HALF TO
WILLIAM H. RHODES, OF SAME PLACE.

SAND-DRIER.

SPECIFICATION forming part of Letters Patent No. 309,195, dated December 16, 1884.

Application filed December 15, 1883. (No model.)

To all whom it may concern:

Be it known that I, GEORGE H. CAMPBELL, of Chicago, county of Cook, and State of Illinois, have invented certain new and useful 5 Improvements in a Sand-Drier, of which the following is a full, clear, and exact description, that will enable others to make and use the same, reference being had to the accompanying drawings, forming a part of this specification.

The object of this invention is to provide an improved apparatus for drying sand and gravel; and it consists of certain novel features in the construction and arrangement of 15 the several parts, whereby the heating and drying process is accomplished with facility.

Figure 1 is a front end elevation of a stove or heating and drying apparatus embodying my improved features; Fig. 2, a vertical trans- 20 verse section; Fig. 3, a vertical longitudinal section in the plane 3 3, Fig. 2, and showing part of the screen B, wall a, and bottom B' broken away; Fig. 4, a central longitudinal section, and Fig. 5 a horizontal section showing the bottom in plan.

Referring to the drawings, A represents a stove or furnace of a rectangular shape, the inclosing side walls, a a', being perpendicular as far as the diaphragm a², and from that 30 point running inward and coming together at the top on a vertical line, as shown in Fig. 2 of the drawings, thus forming sloping sides to cause a free movement of the material being dried, and at the same time utilizing all the heat. The side and rear walls, a, a', and a², are corrugated, as shown in Fig. 5. This arrangement increases the heat-radiating surface by reason of the convolutions, and also stiffens the wire screen B surrounding the corrugated 35 walls, as the outward corrugations are in contact with and form a support for the said screen, which prevents the sand from caking or baking in a mass. The wire screen B comes in contact with each alternate ridge of the corrugated 40 side and end walls, and forms separate channels or passages for the running of the sand or other material. The base or bottom B' of the stove is provided with the perforations a³, which extend around both sides and the back 45 end, as shown in Fig. 5 of the drawings. The

wire screen B is so placed that the lower edge, resting on the base B', divides the holes in the center, so that the sand will run through on each side of the screen. Sheets of perforated metal may be substituted for the wire 55 screen, but the netting shown is preferably used.

B² represents the combustion-chamber; B³, the grate; b, the door affording communication with the combustion-chamber; b', the ash-box, and b² the door opening into the same. The diaphragm a², placed in the combustion-chamber, extends clear across the same, and from the rear to a point near the front of the furnace, thus forming the return-flue a⁴, and at 60 the same time getting the full benefit of the fuel consumed by utilizing all the heat. The hopper C, which forms the receptacle for the material to be operated upon, is quite wide at the top, but is gradually contracted toward 65 the bottom, and its edges rest upon the projecting ledges of the base of the stove. The inclosing-walls of the hopper are provided with the numerous perforations b⁵, which provide for and facilitate the escape of the steam 70 from the heated sand, which would otherwise be forced through the body of the material and out at the top, and which of course add another important feature that greatly assists and facilitates the drying process. This hopper is in turn inclosed by the metallic jacket, (represented by the dotted lines in Fig. 2 of the drawings,) which provides a passage or 75 flue for the escape of the steam driven through the perforated hopper. This jacket also prevents the cold air from striking the exterior surface of the hopper, and thereby retarding the drying of the material. The wire screen or netting B extends clear to the top and on a line with the top of the hopper, as shown 80 in Fig. 2 of the drawings, which arrangement provides another passage for the convenient escape of the steam generated in the damp sand or gravel. The screen-boxes or receptacles D D', placed at each side of and underneath the base of the stove, receive the dry sand or other material, and serve to screen the same, and separate the coarse from the fine. These boxes extend around both sides 85 and the back end, and are attachably connect- 90

ed to the apparatus, and may be readily removed at any time. One means of attaching these boxes is to provide a ledge on each end of the bottom upon which the flanges on the 5 end of the boxes may rest, as shown in Fig. 3. The pipe *d*, connected to the front of and near the top of the apparatus, provides the usual escape for the smoke and unconsumed gases from the furnace.

10 The operation is as follows: The sand is placed in the hopper between the walls *C* and the screen *B*. More or less of the sand is forced through the meshes of the latter and passed down through channels formed by the 15 corrugated surface above mentioned, and passes out through the openings *a*. The bulk of the sand, however, is dried in the chamber, and passes out through openings *a'*, which are divided into two parts by the screen. The 20 moisture expelled by the heat escapes through the perforated outer walls and the space between the corrugated wall and screen.

Having thus described my invention, what I claim as new, and desire to secure by Letters 25 Patent, is—

1. In a sand-drier, the combination of a hopper having openings in its bottom for the escape of sand, a stove having corrugated walls and a screen inclosing said corrugated walls, which, with the screen, form passages 30 for the escape of steam and the sand forced through the meshes of said screen, substantially as described.

2. In a sand-drier, the combination of a hopper having openings in its bottom for the 35 escape of sand, a stove having corrugated walls, and a screen inclosing said corrugated walls, and which divides the openings *a* into two parts, substantially as described.

3. In a sand-drier, the combination, with the 40 stove *A*, of the wire screen or netting *B*, the perforated hopper *C*, and the screening-boxes *D D'*, detachably secured underneath the base of said stove, substantially as and for the purpose set forth.

GEORGE H. CAMPBELL.
